JAMES L. PATTERSON, OF WHEELER STATION, INDIANA.

Letters Patent No. 60,779, dated January 1, 1867.

IMPROVED BROOM-HANGER.

The Schedule referred to in these Letters Patent and making part of the same.

TO ALL WHOM IT MAY CONCERN:

Be it known that I, JAMES L. PATTERSON, of Wheeler Station, in the county of Porter, and State of Indiana, have invented a new and useful device for Hanging up Brooms; and I do hereby declare and make known that the following is a full, clear, and exact description of the same, reference being had to the accompanying drawings, and the letters and figures marked thereon, which form part of this specification.

My said invention consists in a ring to be screwed upon or otherwise attached to the end of a broom handle, provided with a hook or other suitable device for hanging up the same, so that the broom may be readily hung up out of the way, when not in use, as required.

To enable those skilled in the art to understand how to construct and use my invention, I will proceed to describe the same with particularity, making reference in so doing to the aforesaid drawings, in which—

Figure 1 represents a side view of my invention, with the broom attached and hung up; and

Figure 2 is a transverse central section of the same.

A represents the ring which fits upon the end of the broom handle, marked C, being provided with a female screw so as more securely to adhere thereto, by being turned upon the same, or the said interior surface may be without the screw, fitting tightly enough in such case upon the handle to adhere without such provision. B represents a bail attached upon the said ring as shown, which is hooked or suspended upon the peg, pin, or nail, as shown in fig. 1. Instead of being constructed in the form shown, the said arrangement, B, whereby the suspension is effected, may be made in form of a hook, but I prefer the form as herein shown, as being more convenient and symmetrical.

Having described the construction and operation of my invention, I will now specify what I claim, and desire to secure by Letters Patent:

I claim the ring A, in combination with a bail or hook B, arranged and operating substantially as and for the purposes set forth.

JAMES L. PATTERSON.
